(57) CLAIM

The ornamental design for a handbag as shown and described.

DESCRIPTION

FIG. 1 is a front perspective view of a handbag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back perspective view thereof.

The broken lines in the figures depicting the entire strap and attaching hardware, bottom gussets, and monogram logo/latch represent portions of the handbag that form no part of the claimed design. The heavier dashed lines on the body of the handbag depict stitching that forms a part of the claimed design.
